UNITED STATES PATENT OFFICE.

SAMUEL D. LUX, OF NEW YORK, N. Y.

DESIGN FOR A BOX-COVER.

SPECIFICATION forming part of Design No. 21,923, dated October 25, 1892.

Application filed September 9, 1892. Serial No. 445,457. Term of patent 3½ years.

To all whom it may concern:

Be it known that I, SAMUEL D. LUX, of the city, county, and State of New York, have invented and produced a new and original Design for Box-Covers, of which the following is a full, clear, and exact specification.

Reference is to be had to the accompanying drawings, in which Figure 1 represents in perspective a neck-tie box having my new design embodied in the internal cover thereof, and Fig. 2 is a perspective view of the cover removed.

The design consists in the configuration of the cover A, as shown, which represents a novel grouping of figures approximating a series of cigars. Thus the top surface a has in relief a series of parallel figures a', simulating individual cigars, and between said fig-

ures, at the back, appear the pointed figures a², also in relief and appearing as if below the figures a', and at the front appear figures a³, alternating with the front terminals of the figures a'. The figures a² a³ appear as if continuations of each other and merge into the figures a', as if lying beneath the same. The forward defining-lines of the figures a' a³ at the extreme edge a⁴ form scallop-like figures, as shown.

I claim—

The design for a box-cover herein shown and described.

SAM'L. D. LUX.
